The ornamental design for the extremity rehabilitation apparatus, as shown and described.

DESCRIPTION

FIG. 1 is a top perspective view of an extremity rehabilitation apparatus showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom view thereof;
FIG. 8 is a top perspective view showing a user's feet positioned in the foot restraints;
FIG. 9 is a top perspective view showing a user's hands positioned in the hand restraints; and,
FIG. 10 is a perspective view showing the present invention in use with an associated device for anchoring the invention. (The user's feet and hands and other components shown in broken lines are illustrative of environmental structure and do not form a part of the claimed design.)
